UNITED STATES PATENT OFFICE.

EDMUND DE MOULIN AND ULYSSES S. DE MOULIN, OF GREENVILLE, ILLINOIS.

DESIGN FOR A BADGE.

SPECIFICATION forming part of Design No. 31,618, dated October 10, 1899.

Application filed August 19, 1899. Serial No. 727,856. Term of patent 14 years.

To all whom it may concern:

Be it known that we, EDMUND DE MOULIN and ULYSSES S. DE MOULIN, citizens of the United States, residing at Greenville, in the county of Bond and State of Illinois, have invented and produced a new and original Design for a Badge, of which the following is a specification.

This invention relates to a new and original design for a badge.

The essential features of the design reside in a circle representing the cross-section of a log, in the center of which is a shield bearing a crossed beetle and ax on the face and inclining downwardly, the ax being to the left with the bit uppermost and a wedge pointing downwardly thereunder. Five stars are also positioned in horizontal line in the field.

In the drawings, Figure 1 is a plan view of the badge or emblem, showing the design. Fig. 2 is an edge view.

Referring to the drawings, 1 designates a badge or emblem consisting of a disk or circular body provided with a rough periphery

2 and a circular marginal line 3 to represent the bark of a tree, the circular disk or body being in itself an imitation of a cross-section of a tree. The disk or body has on its face a shield 4, and thereover is an ax 5 and beetle 6, crossed on the lower portion of the shield with the bit of the ax extending upwardly and the wedge portion thereof pointing downwardly thereunder. The field of the shield has five stars 7 arranged therein in horizontal alignment. Beneath the shield is arranged a wedge 35 8, which points downwardly.

What is claimed as new is—

The design for a badge, herein shown and described.

In testimony that we claim the foregoing as our own we have hereto affixed our signatures in the presence of two witnesses.
